George E. Sharples
By Horatio E. Bellone

Attorney

UNITED STATES PATENT OFFICE

GEORGE E. SHARPLES, OF CRANSTON, RHODE ISLAND, ASSIGNOR TO D. M. WATKINS COMPANY, A CORPORATION OF RHODE ISLAND

BUTTON

Application filed December 30, 1931. Serial No. 583,841.

My invention relates to separable buttons or emblems of the lapel engaging type.

The essential objects of my invention are the prevention of tearing or braiding the 5 lapel or other engaged fabric by the teeth in their rotary movement of engagement; to simplify the structure and the method of construction of the button, as well as to effect a saving in cost of construction; and to insure 10 an unobstructed swiveling action of the toothed disk.

My invention consists in such parts and combinations of parts, and in such steps and in such successions of steps as fall within the 15 scope of the appended claims.

In the accompanying drawings which form a part of this specification,

Figure 1 is a side elevation of my button, 20 Figure 2, a similar elevation partially in central vertical section,

Figure 3, a section on line 3—3 of Figure 2, and

Figure 4, a section of the lower portion of 25 the back member of my button before assembling, and an elevational section of a portion of the crimping tool or die.

Similar reference numerals indicate similar parts throughout the views.

A front or entrant member 7 includes an 30 ornamental head of any preferred outline fixed to or integral with a shank 8 provided with a thread 9.

The back member or base consists of a circular plate 11 and a central cylindrical elevation 12 provided with an inward bevel in 35 its top as at 13, and with an annular indent 15 at its base; and the plate 11 and the elevation are initially provided with a central bore 16, all as shown in Figure 4.

In this figure is also shown a circular disk 18 provided with a central opening 20 having a beveled face 21 tapering inwardly in a downward direction. Upon the peripheral edge of the upper or front face of the disk 18 45 is an annular series of relatively broad integral teeth 23. The minimum diameter of the opening 20 is slightly greater than the maximum diameter of the elevation 15.

In assembling the disk 18 and back member or plate 11, the former is placed upon the

latter, the elevation 12 sliding through the opening 20 and projecting above the plane of the upper face of the disk 18.

A swaging or crimping tool or die 25, as shown in Figure 4, has an annular groove or recess 27 in the margin of its operating face merging in a centrally located depending conical projection 29. The tool is forced upon and into the elevation 12, radially expanding and depressing the latter to form an externally conical bearing 31 loosely engaging the beveled disk opening 20 and terminating in an annular rolled over lip or flange 32 slidably overlapping the disk 13, as shown in Figure 2. By the described operation the member 18 is rotatably engaged with the front or top face of the member 11 and with the bearing 31 and lip portion 32. Subsequently the bore 16 of the plate is tapped to form an internal thread 33.

The application of this button to a coat lapel is effected by pushing with one hand the shank 8 of the head 7 through the lapel hole. The back plate 11 is then turned by the operator's other hand which advances the plate upon the threaded shank until the teeth 23 contact with the lapel, and sink rectilinearly therein uneffected by the continued rotary movement of the member 11. Hence the teeth cannot abrade the lapel.

I claim:

1. In a button, a head, a shank thereon provided with a screw thread, a back plate provided with a threaded hole adapted to receive the thread of the shank, a stationary bearing upon the front of the plate concentric with the hole, a disk rotatably engaging the bearing and the front of the plate, a terminal annular flange upon the bearing overlapping the disk and in slidable contact therewith, and an annular series of forwardly directed teeth upon the margin of the disk.

2. In a button, a head, a shank upon the head provided with a thread, a back plate, a forwardly directed flaring bearing integral with the center of the plate, said plate and bearing being provided with a central hole, and said hole being provided with a thread engageable with the first thread, a rotatable disk engaging the front of the plate and

provided with a central opening for the reception of the bearing, said opening being provided with a taper conforming with the flaring of the bearing, a lateral flange upon the end of the bearing in sliding engagement with the plate, and forwardly directed teeth upon the margin of the disk.

3. The method of constructing the back members of a separable button consisting in forming a plate and central cylindrical elevation with a central bore and with an inward bevel upon the free end of the elevation, placing loosely upon the plate a disk with a central opening tapering inwardly in a downward direction, said disk being of less thickness than the height of the elevation, thereafter radially expanding and depressing the elevation to externally conform to the bevel of the disk and to overlap the latter, and tapping the bore to form a thread therein.

In testimony whereof I have affixed my signature.

GEORGE E. SHARPLES.
